UNITED STATES PATENT OFFICE

ANTHONY D. GARGOLINSKI, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

WEFT REPLENISHING MECHANISM

Application filed December 30, 1931. Serial No. 583,929.

This invention relates to mechanism for replenishing weft supply in the shuttles of a multi-color automatic loom.

It is the general object of my invention to provide improved and simplified devices for rendering the bobbin-releasing and delivering devices operative upon indication of weft exhaustion. I also provide an improved thread-cutter and shuttle placer for use in combination with my improved weft replenishing mechanism.

My invention further relates to arrangements and combinations of parts which will be hereinafter described and more particularly pointed out in the appended claims.

A preferred form of the invention is shown in the drawings, in which

Fig. 1 is an end elevation of my improved weft replenishing mechanism, with parts of the loom shown in section;

Fig. 2 is a diagrammatic end elevation showing certain operating mechanism for the magazine;

Fig. 3 is an end elevation of certain parts appearing in Fig. 1 but shown in a different position;

Fig. 4 is a plan view of the mechanism shown in Fig. 1;

Figs. 5 and 6 are detail plan views, showing the operation of the thread cutter and placer;

Fig. 7 is a front elevation of my improved mechanism, looking in the direction of the arrow 7 in Fig. 1;

Fig. 8 is a detail sectional plan view, taken along the line 8—8 in Fig. 7;

Fig. 9 is a detail front elevation, taken along the line 9—9 in Fig. 8, and

Figs. 10, 11, 12 and 13 are views similar to Fig. 9 but showing the parts in successive operating positions.

Referring to the drawings, I have shown a magazine having a frame 20 mounted on the breast-beam 21 of a loom in the usual manner and designed to supply fresh bobbins to a shuttle S in a shuttle-box 22 on the usual lay 23. The magazine shown has two bobbin cells or compartments 24 and 25 (Fig. 4) and is adapted to selectively deliver two different kinds or colors of bobbins.

A weft detector 26 (Fig. 4) of a usual commercial form is slidably mounted in a stand 27 and is provided with a forwardly projecting arm 28 adapted to be swung sideways from the stand 27 by the side-slipping of the detector 26 when the detector engages a substantially exhausted weft carrier.

The weft carriers are retained in the magazine cells 24 and 25 by the usual rocking bobbin supports or cradles (not shown), which supports are connected for actuation by vertical slide bars 30 and 31 (Fig. 1). These slide bars are provided with latches 32 (Fig. 7), which when moved upward swing out into position to engage a lifter bar 33 mounted on an arm 34 which swings about a fixed pivot stud 35 (Fig. 1).

A depending arm 36 (Fig. 1) is provided on the rock arm 34, and a stud 37 in the arm 36 extends through a slot 38 in an upright lever 39, pivoted on a fixed stud 40 (Fig. 7) and having a depending portion extending downward and reduced in cross section as indicated at 41. The lever 39 is extended upward beyond the stud 37 and is provided with a stud 42 connected by a coil spring 43 to the stud 37 in the arm 36. A spring toggle is thus provided, by which the lifter bar 33 will be yieldingly retained in either raised or lowered position.

The lever 39 is provided with an additional arm 45 (Fig. 7) extending horizontally and provided with a link 46 loosely underlying the usual latch 47 (Fig. 1) through which the transfer 48 is actuated by the bunter 49 on the lay 23 on weft replenishment.

Fingers 50 (Figs. 4 and 9) are mounted loosely on a rock shaft 51 having bearings 52 on the magazine frame 20. The shaft 51 is free to move angularly relative to the fingers 50 but the fingers 50 are held from axial movement relative to the shaft 51. The outer ends of the fingers 50 extend into notches 54 in the vertically sliding bars 30 and 31.

A color slide 55 (Fig. 4) is loosely mounted on the shaft 51 and is free to move either angularly or axially relative thereto. The slide 55 is provided with lugs or projections 56 at its opposite ends, either one of which may

be moved into a notch or recess 57 (Figs. 8 and 11) in one of the fingers 50.

The color slide 55 is also provided with a segmental projection 58 (Figs. 8 and 9) overlying the hub portion of one of the fingers 50 and also overlying a collar 60 positioned adjacent one of the fingers 50 and secured to the rock shaft 51.

A latch 61 (Fig. 9) is mounted to slide in a transverse recess in the collar 60 and is provided with a reduced end portion 62 extending through the collar 60 into position for engagement by the horizontally extended upper end portion 64 of an indicating lever 65, which lever is mounted on a fixed pivot 66.

The lower end portion 67 (Figs. 1 and 7) of the indicating lever 65 extends forward as indicated in Fig. 4 and is positioned alongside the weft detector stand 27. When the detector 26 slips sidewise to indicate substantial weft exhaustion, the forwardly projecting portion 28 of the detector is swung sidewise against the portion 67 of the indicator lever 65 and thus raises the end portion 64 of the lever from the position shown in Fig. 9 to the position shown in Fig. 11. When in the latter position, the portion 64 engages the reduced portion 62 of the latch 61 and, the latch is moved from the withdrawn position shown in Fig. 9 to the operating position shown in Fig. 11 when the collar 60 is moved angularly, as will be hereinafter described.

The reduced lower end portion 41 of the lever 39 extends into a slot 70 (Fig. 6) in a slide plate 71 which is movably mounted with reference to a stud 72 which extends upward through a slot 73 in said slide plate. The stud 72 is fixed in a stand 75 having guide-ways for a slide 76, on which a combined weft cutter and shuttle placer is mounted.

This cutter and placer comprises a cam plate 80 (Figs. 4 to 6) pivoted at 81 to said slide 76 and having a cutter and placer jaw 82 fixed to said cam plate and extending rearwardly therefrom. The cam plate 80 has a cam groove 84 through which the fixed stud 72 extends and also has a cam surface 85 which engages a stud 86 on the end of the slide plate 71.

A movable cutter jaw 87 (Fig. 1) is pivoted to the fixed jaw 82 at 88 and has a forwardly extending arm 89 provided with a stud 90 engaging a cam surface 91 on the under side of the cutter stand 75 as the cutter slide 76 is moved forward. A suitable spring (not shown) is provided for opening the cutter jaws as the cutter slide moves rearward.

When the loom is operating normally, a shoulder 93 on the cam plate 80 engages a projection 94 on the slide plate 71, as shown in Fig. 4, and the weft cutter and shuttle placer is thus held forward and out of the path of the lay and shuttle.

A cam bar 95 (Fig. 1) is vertically movable

in guide-ways on the magazine frame 20 and at its upper end is pivoted to the end of the lifter bar 33 previously described. At its lower end the bar 95 is provided with a cam surface 97 engaging a stud 98 on an arm 99 as the bar 95 is raised. A bobbin release member 100 is pivoted on the stud 98 and is connected to the magazine frame by a link 101. As the bar 95 is raised, the member 100 is thus withdrawn to release any bobbin which may be held in transfer position.

The rock shaft 51 is regularly oscillated in any convenient manner, as by the arm 110, link 111, cam lever 112 and cam 113 shown in Fig. 2. The rock shaft 51 is thus given one complete oscillation for each alternate beat of the lay.

The color slide 55 is selectively moved axially on a lever 120 (Figs. 1 and 3) pivoted at 121 on the magazine frame 20 and having an upwardly extending arm 122 provided with a stud 123. This stud 123 engages the upper surface of a cam bar 124 having a slot 125 through which the stud 121 extends.

The bar 124 is suitably connected, as through a chain 126 (Fig. 2), to some convenient part of the box motion, so that the cam bar 124 will be moved upward or downward in accordance with the movements of the boxes.

The bar 124 has a cam recess 130 (Fig. 3) in its upper surface, adapted to receive the stud 123 of the lever 120 as the bar 124 slides downward, this downward movement being effected by a spring 131 which acts to force the bar 124 downward whenever tension on the chain 126 is released. A spring 132 is provided to rock the lever 120 to the right in Fig. 3 when the stud 123 is free to enter the cam slot 130.

Having described the details of construction of my invention, the method of operation is as follows:

The parts are normally in the position shown in Figs. 4 and 9, with the slide bars 30 depressed, and the lever 39 in the position shown in Fig. 7, and with the weft cutter and shuttle placer in the forward position shown in Fig. 4.

Assuming that the color slide 55 is positioned as shown in Fig. 1, the lug 56 at the right-hand end of the color slide 55 will be positioned in the notch 57 of the right-hand or forward finger 50, as shown in Fig. 9.

As the collar 60 is rocked with the shaft 51, a shoulder 133 (Fig. 10) thereon engages the projection 58 on the color slide 55 and rocks the color slide. The notch or recess 57 in the finger 50 is of such extent, however, that the lug 56 moves freely in the notch 57 and no motion of the finger takes place, the position of the parts at the end of the movement being as shown in Fig. 10.

If, however, substantial exhaustion of weft has caused the member 64 to be raised to the

position shown in Fig. 11, the latch 61 will be shifted in the collar 60 and will engage the projection 58 on the color slide 55, by which engagement the color slide is rocked through a greater arc, thus raising the finger 50 and sliding bar 30 from the position shown in Fig. 11 to the position shown in Fig. 12. In this raised position, the latch 32 is free from the portion 135 of the fixed magazine frame 20 with which it is normally engaged and the latch thereupon swings outward over the upper face of the lifter bar 33.

As the rock shaft 51 is moved clockwise in Fig. 13, the lug 56 engages the right-hand end of the notch 57 and depresses the finger 50, thus carrying the lifter bar 33 downward and swinging the lever 39 to release the weft cutter and shuttle placer.

This allows the cutter slide 76 to move rearward, during which movement the cam slot 84 cooperates with the stud 72 to swing the cutter jaw and shuttle placer 82 angularly, causing the shuttle S to be moved to fully boxed position.

As the cutter slide is thereafter forced forward by the lay, the cam surface 85 on the cam plate 80 engages the stud 86, pulling the slide plate 71 downward, as viewed in Figs. 4, 5 and 6, and reversing the position of the lever 39. Such reversal raises the lifter bar 33, which moves the depressed slide bars 30 upward and thus restores the parts to their original position.

It will thus be seen that I have provided a direct connection between the weft detector and the selecting and releasing mechanism of the magazine. By so doing, I am able to omit the chopper lever and associated parts previously used in this type of mechanism.

I have also provided a positive connection between the weft cutter and shuttle placer and the bobbin release by which the bobbin will be normally released as the lay closely approaches front center, the cutter slide being moved forward as a result of the engagement of one end of the front box plate P (Fig. 5) with an abutment 140 on the cutter slide.

If, however, the shuttle is so widely misplaced that the shuttle placer 82 engages the side of the shuttle, the cutter slide 76 will be pushed forward earlier in the cycle of movement of the lay and the bobbin will be released before the lay reaches front center.

All parts of my improved mechanism are of a simple construction and operation and the various movements are accomplished with the least possible delay.

Having thus described my invention and the advantages thereof, I do not wish to be limited to the details herein disclosed, otherwise than as set forth in the claims, but what I claim is:—

1. In a weft replenishing drop box loom, a multi-color magazine, slide bars movably mounted thereon, fingers engaging said slide

bars, a rock shaft, means to regularly oscillate said shaft, a color slide axially movable on said rock shaft to engage a selected finger, a member fixed to said shaft, a connecting device mounted in said member and movable to operative and inoperative positions relative to said color slide, a weft detector, and means engageable by said weft detector on indication of substantial weft exhaustion and actuated thereby to move said connecting device to operative position in said member.

2. The combination in a weft replenishing loom as set forth in claim 1, in which means is provided through which said rock shaft positively returns each slide bar to lowered position after said bar has been raised through the operation of said connecting device.

3. The combination in a weft replenishing loom as set forth in claim 1, in which a shoulder on said member positively engages and moves said color slide in a direction opposite to the movement effected by said connecting device.

4. The combination in a weft replenishing loom as set forth in claim 1, in which said member is provided with a recess therein and in which said connecting device comprises a latch normally seated in said recess but slidable outward into position to engage a portion of the color slide, and means to move said latch.

5. The combination in a weft replenishing loom as set forth in claim 1, in which said member is provided with a recess therein and in which said connecting device comprises a latch normally seated in said recess but slidable outward into position to engage a portion of the color slide, and means to move said latch, said latch being returned to inoperative position by gravity when released.

6. The combination in a weft replenishing loom as set forth in claim 1, in which the means engaged by the weft detector comprises a bent lever mounted on a fixed pivot and having its upper end horizontally extended to engage said connecting device and its lower end forwardly extended to a position in which it may be engaged by a forwardly extended portion of said weft detector.

7. The combination in a weft replenishing loom as set forth in claim 1, in which the bar-engaging fingers are loosely mounted on said rock shaft but are held from axial movement relative thereto.

8. The combination in a weft replenishing loom as set forth in claim 1, in which a cam on the bottom shaft is connected to regularly oscillate the rock shaft.

9. The combination in a weft replenishing loom as set forth in claim 1, in which the color slide is provided with projections selectively positioned in segmental notches in said fingers and having lost motion relative to said fingers.

10. The combination in a weft replenishing loom as set forth in claim 1, in which the means for moving the color slide axially comprises a lever engaging said slide and having a stud thereon, a spring to move said lever in one direction, and a slidable cam bar effective to move said lever in the opposite direction.
11. The combination in a weft replenishing drop box loom as set forth in claim 1, in

which the means for moving the color slide axially comprises a lever engaging said slide and having a stud thereon, a spring to move said lever in one direction, and a slidable cam bar effective to move said lever in the opposite direction, the movements of said cam bar being co-ordinated with the movements of the drop boxes. 70
